(57) **CLAIM**

The ornamental design for a milking claw for a milking machine, as shown and described.

DESCRIPTION

FIG. 1 is a perspective view of a milking claw for a milking machine according to an embodiment of the design;

FIG. 2 is a right side view thereof;

FIG. 3 is a left side view thereof;

FIG. 4 is a front view thereof;

FIG. 5 is a back view thereof;

FIG. 6 is a top view thereof; and,

FIG. 7 is a bottom view thereof.

The broken lines depict unclaimed features of the milking claw for a milking machine that form no part of the design claim but are shown for purposes of illustration.

1 Claim, 7 Drawing Sheets
